UNITED STATES PATENT OFFICE.

RICHARD WEBB BURNETT, OF MONTREAL, QUEBEC, CANADA.

VENTILATOR.

1,215,341.

Specification of Letters Patent. Patented Feb. 13, 1917.

Application filed June 15, 1914. Serial No. 845,238.

To all whom it may concern:

Be it known that I, RICHARD WEBB BURNETT, residing at the city of Montreal, Province of Quebec, Dominion of Canada, have 5 invented certain new and useful Improvements in Ventilators; and I do hereby declare that the following is a full, clear, and exact description thereof.

My invention relates to ventilators for 10 refrigerator cars, and more particularly to the ventilators of the type combined with the hatch through which the ice is loaded, but it is applicable to cars of all types.

The object of my invention is to provide 15 a ventilator which will be cinder-proof, and simple and inexpensive to construct; and to this end the invention may be said briefly to consist of a ventilating hatch cover comprising a top having three flanged sides and 20 a non-flanged side and a ventilating member secured the last mentioned side comprising a screen rigidly secured in place and consisting of a pair of spaced sheets of material pervious to air and adapted to have 25 the outer sheet act as a baffle for so retarding the speed of cinders passing through that they are stopped by the inner sheet; an additional feature being the discharge of the cinders from the intervening space.

30 For full comprehension, however, of my invention, reference must be had to the accompanying drawings, in which similar reference characters indicate the same parts, and wherein:

35 Figure 1 is a plan view of my improved device partly in section; Fig. 2 is a front elevation thereof illustrating particularly the ventilating member; Fig. 3 is a vertical sectional view taken on line A A Fig. 1.

40 My invention is illustrated applied to a box car of the ordinary type having hatches in its roof. One of these hatches is illustrated at 2 and consists of four wooden walls projecting slightly above the roof. These 45 walls are protected by a member 3 of angle cross-section inclosing the same and constructed and arranged to have one flange lie in flat contact with the car roof and the other flange project slightly above each of 50 the walls.

The cover I provide for each of these hatches is constructed of sheet metal and consists of an inclined top 4 having three flanged sides 5, 6 and 7 formed integrally therewith, the sides 6 and 7 being tapered to side 5 to accommodate the incline of the

top. The fourth side of the cover is constituted by a ventilating member or screen consisting of a pair of oblong rectangular frames 8 and 9 spaced apart and rigidly secured together by a series of pipe ferrules 12 mounted on bolts 13, the whole being rigidly secured to the cover by means of the turned in edges 14 of the tapered sides, which edges form the ends of the outer frame 8 to which is riveted a member 15 of inverted U cross-section secured to the underside of the top and riveted to both ventilating member and cover. In order to reinforce the cover against the stresses and strains to which hatch covers for cars are subjected, a stiffening band 25 extends completely around the cover including the screen to all of which it is riveted. This band constitutes the lower side of the outer frame 8 of the screen.

Each frame of the screen is completely covered by a sheet of wire netting 17, the bottom of the screen being open and a clear space being provided between the sheets of 80 the screen, the purpose being to permit cinders and dirt which pass through the outer sheet and are collected between the sheets to fall out when the cover is lifted.

In order to afford means for closing the 85 ventilating side of the cover when ventilation is not desired a door 20 is hinged to the free edge of the inclined top and is adapted to be swung down in front of the outer frame 8 when in closed position and when 90 in open position to lie back in flat contact with the top.

The cover is hinged to the car roof by means of a pair of straps 21 secured as at 95 30 to the corners of the cover formed by the ends of side 5 and tapered sides 6 and 7. Each of these straps is folded back upon itself at approximately midway its length as at 26 and the folded back portion is turned out at right angles thereto about 100 midway the length thereof as at 28. These folded back portions are pivotally mounted upon a hinge bar 31 which in turn is journaled in the upturned edges 32 of a pair of plates 33 secured to the car roof.

In order to lock the cover in place a hasp 34 is secured to the stiffening band midway the length of the ventilating member and is constructed and arranged to rest in a bracket 110 35 secured to the roof of the car and having its ends turned up as at 36 to carry a cotter pin 37. The cotter pin when in place pre-

vents the hasp being lifted from the bracket while the turned up ends thereof intersect the path of the door and consequently serve to lock it in place as well as the cover. 5 When it is desired to open the door the cotter pin is removed and the cover lifted sufficiently to allow the door to clear turned up ends, this being accomplished the cover may be lowered again and the cotter pin 10 once more inserted in the bracket.

To facilitate lifting, the top of the cover is provided with a handle 40 and is reinforced by a member of angle cross-section 41 extending completely across the same and secured to the underside thereof, the handle, 15 top, and angle member being rigidly secured together by rivets passed therethrough.

What I claim is as follows:—

1. In a car the combination with an 20 ice loading hatch, of a combined sealing and ventilating member consisting of a unitary sheet-metal cover having one side hingedly secured to the car and having its opposite side open for ventilating purposes; a screen 25 extending across said opening and being rigidly secured to the cover and movable in unison therewith, said screen consisting of a pair of frames of equal dimensions spaced apart and rigidly secured together, each 30 frame having a sheet of wire netting stretched completely across the same, the outer sheet being adapted to act as a baffle.

2. A hatch cover for box cars consisting 35 of a unitary sheet metal body having three flanged sides, a ventilating member or screen completing the unflanged side and consisting of a pair of oblong rectangular frames, means rigidly securing such frames together in spaced relation, a member of in-

verted U cross-section riveted to both ventilating member and cover, and a stiffening band extending completely around the cover and screen and riveted in place, the said band constituting a part of the outer frame 40 of the screen, a pair of sheets of wire netting completely covering the said spaced frames the outer of said sheets being adapted to act as a baffle, the said screen having an opening in its bottom communicating with the interior thereof for the purpose set forth. 45

3. A hatch cover for box cars having a screen rigidly secured thereto for ventilating purposes, said screen consisting of a pair of spaced sheets of material pervious to air, 55 said sheets being relatively immovable.

4. In a car the combination with an ice loading hatch, of a combined sealing and ventilating member consisting of a unitary sheet metal cover having one side open, a 60 stiffening member of comparatively narrow width surrounding and being rigidly secured to the cover and extending across said open side, and a screen member extending across said opening and being rigidly secured to the cover and stiffening member, 65 said screen consisting of a pair of spaced relatively immovable sheets of wire netting, and means hingedly connecting the cover to the car. 70

In testimony whereof I have signed my name to this specification in the presence of two witnesses.

RICHARD WEBB BURNETT.
